ELECTRIC SHAVER

Maarten Willem van Lelyveld, Drachten, Netherlands, assignor to United States Philips Corporation

Filed June 24, 1967, Ser. No. 17,846

Claims priority, application Switzerland Dec. 27, 1968

Term of patent 14 years

Int. Cl. D28—03

U.S. Cl. D95—3

FIG. 1 is a perspective view of the electric shaver showing my new design;

FIG. 2 is a side elevational view thereof;

FIG. 3 is an elevational view of the opposite side thereof;

FIG. 4 is a front elevational view;

FIG. 5 is a rear elevational view;

FIG. 6 is a top plan view thereof;

FIG. 7 is a bottom plan view thereof.

I claim:

The ornamental design for an electric shaver, as shown.
